UNITED STATES PATENT OFFICE.

FRANK F. SCHMIEGE, OF APPLETON, WISCONSIN.

WIRE-SEAMING MACHINE.

Application filed August 2, 1926. Serial No. 126,617.

This invention relates to wire seaming machines, and more particularly to a machine adapted for sewing the ends of wire strips together to form long continuous pieces.

An important object of the invention is to provide a novel machine of the semi-automatic type adapted for stitching the ends of wire strips together.

10 A further object is to provide novel means for positioning the strips adjacent the sewing mechanism, the positioning means being adapted to protect the edges of the wire.

15 A further object is to provide automatic means for successively feeding the wire used as a stitching means upwardly between the adjacent ends of the wire strips whereby it may be manually inserted through the wire to complete each successive stitch.

20 A further object is to provide novel means for holding the wire stationary and to advance the sewing mechanism after each successive strip.

A further object is to provide an endless belt mechanism adapted to receive the end 25 of the wire used in stitching after it is inserted through one of the wire sheets and to return the free end of the stitching wire upwardly between the adjacent ends of the 30 sheets.

A further object is to provide means for 35 releasing the stitching wire from the endless belt referred to in order that the wire may be drawn upwardly against the wire sheets to complete each successive stitching operation.

Other objects and advantages of the invention will become apparent during the course 40 of the following description.

In the drawings I have shown one embodiment of the invention. In this showing:

Fig. 1 is a side elevation of the machine, parts being shown in section;

Fig. 2 is a detail section on line 2-2 of 45 Fig. 1;

Fig. 3 is a similar view on line 3-3 of Fig. 1;

Fig. 4 is an enlarged section on line 4-4 of Fig. 1;

50 Fig. 5 is an enlarged detail section taken substantially on line 5-5 of Fig. 1;

Fig. 6 is a fragmentary side elevation of a portion of the stitching-wire feeding means, parts being broken away and parts 55 being shown in section;

Fig. 7 is an enlarged side elevation of the carriage and associated elements;

Fig. 8 is an enlarged side elevation of a portion of one end of the apparatus, parts being shown in section;

Fig. 9 is a detail sectional view through a portion of the carriage feeding mechanism;

Fig. 10 is a detail section on line 10-10 of Fig. 8;

Fig. 11 is a similar view on line 11-11 of Fig. 8;

Fig. 12 is a detail perspective of the drive pulley and shaft;

Fig. 13 is a detail end elevation of the driving end of the apparatus;

Fig. 14 is a detail section on line 14-14 of Fig. 1;

Fig. 15 is an enlarged end elevation of a portion of the carriage feeding end of the apparatus;

Fig. 16 is a detail perspective of the wire sheet holding device; and

Fig. 17 is a detail of a pair of shaft sections and the coupling means therefor.

Referring to Fig. 4, the numeral 10 designates a base member preferably formed of wood, and mounted upon any suitable supporting means (not shown) such as a table or the like. A pair of tracks 11 are arranged on opposite sides of the base 10, each track 80 being formed of angle-iron and including a vertical portion 12 secured against opposite edges of the base and a horizontal portion 13 forming the track means.

A carriage 15 is mounted to travel on the 90 tracks 11, by suitable wheels 16 journalled on axles 17. This carriage includes a base portion 18 having depending side members 19, the lower ends 20 of which extend outwardly beneath the rail portions 13 to prevent upward movement of the carriage, as will be apparent. The carriage is provided with a pair of spaced vertical bearing standards 21, as shown in Figs. 1, 4 and 7. A pulley 22 is arranged between the standards 21 100 and is supported by and fixed to a shaft 23 journalled in the standards 21. The shaft 23 extends outwardly beyond the carriage 15 and this shaft will be referred to in detail later.

Above the pulley 22, an idler roller 24 is supported upon the shaft 25 which is arranged forwardly of the bearing brackets, as clearly shown in Fig. 4. The ends of the shaft 24 are journalled in one end of take-up 110

levers 26, the levers being pivoted intermediate their ends upon a shaft 27 which is journalled in the standards 21. The opposite ends 28 of the levers are normally urged 5 downwardly by springs 29, the lower ends of the springs being suitably connected to the carriage as will be understood. A shaft 30 is secured to one of the bearing brackets, substantially in horizontal alinement with 10 the shaft 25, and supports a roller 31 arranged adjacent the bearing bracket to which the shaft 30 is secured. The opposite end of the shaft 30 is spaced from the opposite bearing bracket, for a purpose to be described, and supports a separate reduced roller 32. The shaft 30 preferably has one end threaded and adapted to be inserted in a threaded opening in the bearing bracket to which it is secured, the opposite end of the 15 shaft preferably being provided with a screw driver slot or the like 33 by means of which the shaft may be tightened in position. Rearwardly of and above the shaft 30, another shaft 34 is journalled at opposite ends 20 in the bearing brackets 21 and supports a roller 35. An endless belt 36 passes beneath the pulley 22, over the pulley 24, beneath the roller 31, over the roller 35 and thence back beneath the pulley 22, as clearly shown 25 in Figs. 4 and 5. It will be obvious that rotation of the shaft 23 is adapted to drive the belt 36, the purpose of which will be described. A stitching wire guide 37 is arranged with its lower end adjacent the 30 rollers 31 and 35, as shown in Figs. 5 and 6. This guide is formed of sheet metal and has its edges 38 and 39 slightly overlapped and inclined downwardly and toward the left, as viewed in Fig. 6. The guide is adapted to 35 be supported by a bracket 40, the opposite end of which is secured to a vertical member 41 preferably formed integral with the carriage 15.

Referring to Fig. 4, the numerals 42 and 42' designate wire sheets, the ends of which are to be stitched together. A positioning member 43, preferably formed of steel is adapted to properly position the edges of the wire sheets during the stitching operation. 40 A pair of positioning members proper, indicated by the numerals 44 and 45, are arranged on the end of the member 43, the latter being bifurcated as at 46. One of the bifurcated ends of the member 43 is inclined 45 downwardly as at 47 while the other is inclined upwardly as at 48. The members 44 and 45 obviously are inclined similarly to the ends of the member 43, and may be secured to such ends in any suitable manner 50 such as by soldering or brazing. The members 44 and 45 are substantially U-shaped to receive the edges of the wire sheets, as shown in Fig. 4.

Means are provided for moving the carriage 15 in successive steps toward the right,

as viewed in Fig. 1, and means also are provided for limiting the movement of the carriage toward the left. Referring to Fig. 4, the numeral 51 designates an arm secured to the carriage 15 and extending rearwardly 70 thereof. A pull rod 52 is provided with an eye 53 surrounding the reduced end 54 of the arm 51, and a cotter-pin 55 retains the eye in position. The rod 52 is formed in a plurality of sections 53', the ends of which are 75 adapted to be joined by couplers 54', for a purpose to be described. The end of the outermost rod section 53' is turned forwardly at right angles as at 55' to extend through a pivoted bar 56, as shown in Fig. 8. The 80 bar 56 is provided with ratchet teeth 57, and extends through a slot 58 formed in an operating bell-crank lever 59. The bar 56 is supported in the bell crank lever by a roller 60, and a pawl tooth 61 is adapted to engage the teeth 57. The upper end 62 of the pawl projects upwardly beyond the end of the bell crank lever and is normally urged downwardly by a spring 63. The bell crank lever 59 is pivotally connected as at 64 to a bracket 65 arranged on the table or support previously referred to. An operating rod 66 is pivotally connected to the free end of the bell-crank lever as at 69. As shown in Fig. 1, a shaft 67 is journalled in suitable brackets 68 and is provided at one end with a crank 69 to which the lower end of the rod 66 is connected. A treadle 70 is splined to the shaft 67 as at 71 and is adapted to be moved along the shaft 67 by a U-shaped member 72 supported on the floor or the like by rollers 73. It will be obvious that depression of the treadle 70 is adapted to pull the rod 66 downwardly and swing the upper end of the bell crank 105 lever 69 outwardly, thus pulling the bar 56 and rod 52 to move the carriage 15 to the right, as viewed in Fig. 1.

A bumper bracket 74 is arranged over the tracks 13 and is adapted to slide thereon as 110 will be apparent. The bracket 74 is provided at one end with a relatively short vertical arm 75 and at its opposite end with a relatively tall arm 76. The positioning member 43 is secured to the upper end of the arm 76 by screws or the like 77. A shaft 78 projects through the arms 75 and 76 and is threaded at one end as at 79. A nut 80 is threaded on the shaft 78 and engages the inner face of the arm 76. A nut 81 is threaded on the outer end of the shaft 78, against the outer face of the arm 76 and a bumper 82 is secured to the nut 81 and contacts with the adjacent end of the carriage 15 to limit its movement toward the left, as viewed in 125 Fig. 7. The shaft 78 is formed of a plurality of sections 79 connected by couplers 80 having set screws 81 adapted to clamp against the adjacent ends of the shaft sections. One of the shaft sections 79 extends 130

through a guide bracket 82 which is slideable upon the tracks 11.

A worm-shaft 83 is connected to the adjacent end of the outermost shaft section 79 by a coupling 84 secured in position by bolts 85. The shaft 83 is journaled in bearings 86 preferably carried by an integral base 87. As shown in Figs. 1 and 9, a ratchet wheel 87 having ratchet teeth 88 thereon surrounds the shaft 83 between the bearings 86, and is internally threaded to engage the threads of the worm shaft. A collar 89 freely surrounds the shaft 83 between the ratchet wheel and one of the bearings 86. The collar 89 is provided with an integral arm 90 projecting outwardly therefrom and pivotally connected at its outer end as at 91 with the upper end of a rod 92. The lower end of the rod 92 is connected to the outer end of a crank 93 secured to the shaft 67, as shown in Fig. 1. A pawl 94 is pivotally connected to the arm 90 as at 95 and engages the teeth 88 of the ratchet wheel. A regulating member 96 is arranged with its upper end adapted to contact with the pawl 94, the lower end of the regulating device being secured to one of the bearings 86 and adapted to be adjusted vertically to vary the movement of the ratchet wheel upon upward movement of the arm 90, in a manner to be described.

Means are provided for driving the pulley 22 and the endless belt associated therewith. As shown in Figure 17, the shaft 23 is formed of a plurality of sections 97 adapted to be secured together by couplings 98 secured to the adjacent ends of the shaft sections by set screws 99. The shaft sections 97 are associated with a positive drive clutch 100 to be driven thereby. As shown in Figs. 1 and 11, the clutch comprises a cylindrical member 101 having a cap 102 arranged on one end and provided with an opening slidably receiving the adjacent section of the shaft 23. This shaft section is provided with a lug 103 secured thereto by a screw 104, or formed integral with the shaft section. This lug is adapted to contact with the lug 105 secured within the cylinder 101. As previously stated, the adjacent section of the shaft 23 is slideable in the cap 102 and it will be apparent that when the lug 103 slides inwardly beyond the lug 105 there will be no positive connection between the shaft 23, and the clutch whereby the latter is freely rotatable.

A shaft 106 is secured to the clutch and is rotatable in a bearing 107 slidably supported upon the tracks 11. Collars 108 are secured to the shaft 106 on opposite sides of the bearing 107 whereby the bearing is caused to slide along the tracks when the shaft 106 is moved longitudinally in a manner to be described. The bearing 107 may be provided with a roller 109 at one side to support the

rod 52. Outwardly of the bearing 107 and collars 108, the shaft 106 is secured to a polygonal shaft section 110, as shown in detail in Fig. 12 of the drawings. The polygonal shaft 110 extends through a pair of spaced bearings 111 preferably formed integral with the bracket 65, as shown in Fig. 8. Collars 112 surround the shaft 110 to rotate within the bearings 111. It will be obvious that the collars 112 are provided with openings corresponding in shape to the cross sectional shape of the shaft 110 whereby the latter is slidably supported in these collars. A pulley 113 surrounds the shaft 110 between the bearings 111, this pulley being provided with a central opening 114 corresponding in shape to the cross sectional shape of the shaft 110 whereby rotation of the pulley is adapted to effect rotation of the shaft 110, but the latter is adapted to slide longitudinally within the pulley.

It is desirable to arrange the guide 37 with its upper end between the adjacent edges of the wire sheets, as shown in Figs. 4 and 5. This arrangement is employed so that the stitching wire 115 may be fed upwardly between the adjacent edges of the wire sheets by the operation of the belt 36. In order to properly support the wire in position for the stitching operation, I prefer to employ a pair of elongated blocks 116 and 117 arranged forwardly and rearwardly of the base 10, as shown in Fig. 4. For the sake of illustration, these blocks have been omitted from the other figures of the drawing, with the exception of Fig. 7. These blocks extend throughout the length of the tracks 113 and are secured to the base 10 by cleats 118, the upper ends of the blocks being rigidly connected to each other by a cross-bar 119. A clamping bracket 120 is secured against the upper faces of the blocks 116 and 117 adjacent each end as shown in Figs. 4 and 7. These brackets receive screws 121 having thumb nuts 122 at their upper ends, the screws being adapted to operate clamping members 123. The clamping members 123 are elevated when the wire is placed in position as shown in Fig. 4, and are adapted to be secured downwardly to clamp the wire to prevent movement thereof during the stitching operation. The wire sheets may be supported upon suitable rolls (not shown) arranged rearwardly of the apparatus, the sheets 42 being adapted to be fed directly across the top of the block 117. The sheet 43 is adapted to be fed beneath the blocks 116 and 117, upwardly around the forward face of the block 116 and then rearwardly across the top of the latter block.

The operation of the apparatus is as follows:

The carriage 15 is arranged toward the left side of the apparatus, as viewed in

Fig. 1, a sufficient number of shaft sections 79 being removed to permit the carriage to be arranged as described. A suitable number of the shaft sections 97 are connected in the shaft 23 to properly elongate this shaft. With the wire sheets arranged in the position shown in Fig. 4, one end of the stitching wire is secured to one edge of one of the wire sheets near one end thereof. The free end of the wire is then fed downwardly between the wires of the other sheet, near the edge thereof and is fed between the belt 36 and the roller 31. With the clutch 100 in the position shown in Fig. 1, the pulley 22 will be rotated from a suitable source of power connected to the pulley 113. Thus the roller 31 will be rotated and the free end of the wire will be fed around this roller and upwardly through the guide 37 whereupon it is grasped by the hand of the operator. The treadle 70 is then depressed, pulling the rod 66 downwardly and swinging the bell crank lever 59. The pawl 61 draws the bar 56 outwardly thus moving the carriage to the right. This action causes the stitching thread to work its way along the roller 31 until it slides off to the roller 32, whereupon the treadle 70 is further depressed, and the operator swings the free end of the wire out of the guide 37 between the edges 38 and 39 thereof. This further depression of the treadle 70 causes the stitching wire to slide off the end of the roller 32, whereupon the operator may pull the stitching wire upwardly to complete the stitch. The stitch thus formed includes a portion projecting downwardly through one of the wire sheets, and thence upwardly between the sheets. The free end of the wire is then inserted between wires of the other sheet, near the edge thereof, the free end of the wire again being grasped between the belt 36 and roller 31 in the manner previously described. Thus it will be apparent that in the successive stitching operations, the stitching wire is whipped back and forth substantially in a figure 8 path to secure the wire sheets together. It will be apparent that depression of the treadle is adapted to move the carriage to the right by swinging the bell crank lever 59, and movement of the carriage is limited by contact between the end of rod 23 and the inner end of the shaft 106, at which time the clutch lugs will be disengaged. After each successive stitch is pulled upwardly, after being released from the roller 32, the treadle 70 is released. Any suitable means may be employed for returning the carriage to normal position, and in the drawings I have shown a spring 124 connected between the carriage and the vertical arm 76. Similarly a spring 125 is connected between the bell crank lever 59 and the adjacent bearing 111, to return the bell crank lever to normal position. Obviously,

inward movement of the carriage will be limited by contact with the bumper, and further movement of the bell crank lever 59 inwardly causes the clutch lugs 103 and 105 to engage, whereby rotation of the belt 136 ⁷⁰ may be effected for starting the next stitch. When the treadle 70 is released the arm 90 is moved upwardly and the pawl 94 rotates the wheel 87. The threads in the wheel 87 engaging the threads of the worm shaft 83, ⁷⁵ cause the latter to be moved inwardly, thus advancing the bracket 74 and bumper 82 so that the carriage is in position for the next stitch. The stitching wire is then inserted between the wires of one of the sheets ⁸⁰ in the manner described, and after the end of the wire has passed upwardly through the guide 37, the treadle 70 is depressed sufficiently to disengage the clutch members. Thus it will be apparent that movement of the carriage to the right is effected by depression of the treadle to release the stitching wire from the roller 32, and the operation of the worm 83 when the treadle is released serves to advance the carriage step ⁸⁵ by step. This step-by-step movement causes the bar 52 to move with the carriage, thus causing the teeth of the bar 56 to slide beneath the pawl 61. As the carriage advances, successive shaft sections 97 and rod ⁹⁰ sections 53 are removed, and shaft sections 79 are added until the stitching operation is completed. It will be obvious that for relatively narrow wire sheets, it will be unnecessary to change the shafts and rods ⁹⁵ referred to.

The feed of the rod 83 may be varied by vertically adjusting the member 96, it being apparent that the pawl 94 cannot engage the ratchet teeth until the arm 90 is moved upwardly a sufficient distance to permit the pawl to be released from the adjusting member 96.

The members 44 and 45 not only serve to position the edges of the wire sheets and permit the upper end of the guide to project therebetween, but also protect the edges of the sheets. The stitch may be varied by employing different positioning members the U-shaped portions of which are arranged ¹¹⁰ varying distances apart. The stitching wire is inserted through the wire sheets by passing it through the space between the inner ends of the bifurcated arms 47 and 48.

It is to be understood that the form of the invention herewith shown and described is to be taken as a preferred example of the same and that various changes in the shape, size and arrangement of parts may be resorted to without departing from the spirit ¹²⁰ of the invention or the scope of the subjoined claims.

I claim:

1. Apparatus of the character described comprising holding means adapted to posi- ¹²⁵

- tion adjacent edges of sheets of wire in slightly spaced relation, and means adapted to receive a stitching wire inserted between the wires of one sheet and to return the end 5 of the stitching wire between the adjacent edges of the sheets.
2. Apparatus of the character described comprising means for holding the adjacent edges of a pair of sheets of wire parallel to and slightly spaced from each other, a 10 guide having an outlet end arranged between the adjacent edges of the sheets, and means adapted to receive the end of a stitching wire inserted between the wires of one sheet and to insert the wire through the opposite end of said guide whereby it will be passed between the adjacent edges of the sheets.
3. Apparatus of the character described comprising a pair of substantially U-shaped members adapted to receive adjacent edges of a pair of sheets of wire to hold them adjacent and parallel to each other, and means for receiving the end of a stitching wire inserted between the wires of one sheet and to return it between the adjacent edges of the sheets.
4. Apparatus of the character described comprising a pair of members adapted to support the adjacent edges of a pair of sheets of wire parallel to and slightly spaced from each other, a guide arranged with one end between the adjacent edges of the sheets, and feed means arranged adjacent the other end 35 of said guide, said feed means being adapted to receive the end of a stitching wire inserted between the wires of one sheet and to insert it through the last named end of said guide.
5. Apparatus of the character described comprising a pair of members adapted to support the adjacent edges of a pair of sheets of wire parallel to and slightly spaced from each other, a guide arranged with one 45 end between the adjacent edges of the sheets, feed means arranged adjacent the other end of said guide, said feed means being adapted to receive the end of a stitching wire inserted between the wires of one sheet and to insert it through the last named end of said guide, and means for effecting the release of the stitching wire from said feeding means.
6. Apparatus of the character described comprising a pair of members adapted to support the adjacent edges of a pair of sheets of wire parallel to and slightly spaced from each other, a guide arranged with one 55 end between the adjacent edges of the sheets, feed means arranged adjacent the other end of said guide, said feed means being adapted to receive the end of a stitching wire inserted between the wires of one sheet and to insert it through the last named end of said guide, means for effecting the release 60 of the stitching wire from said feeding
- means, and means for effecting a step by step movement of said guide and said feed means as the stitching wire is successively released from said feeding means.
7. Apparatus of the character described 70 comprising means for holding a pair of sheets of wire with two of the edges thereof parallel and slightly spaced from each other, a guide arranged with its upper end projecting between the adjacent edges of the sheets, means including a pulley and an endless belt for receiving the end of a stitching wire inserted through the wires of one sheet and to insert it through the opposite end of said guide, means for effecting the release 75 of said stitching wire from said pulley and said belt, and means for moving said guide and said feeding means longitudinally with respect to the adjacent edges of the sheets after the stitching wire is released from said 80 feeding means.
8. Apparatus constructed in accordance with claim 7, provided with a carriage adapted to support said guide and said feeding means, and a trackway adapted to support 85 said carriage for longitudinal movement with respect to the adjacent edges of the sheets.
9. Apparatus of the character described comprising a pair of stationary U-shaped 90 members adapted to receive edges of wire sheets to hold them parallel to and slightly spaced from each other, a carriage longitudinally movable with respect to the adjacent edges of the sheets, a guide carried by said carriage and having its upper end projecting between the adjacent edges of the sheets, feeding means including a pulley and an endless belt adapted to receive a stitching wire inserted between the wires of one sheet 100 and adapted to insert it through the opposite end of said guide, a treadle having a bias to normal position and movable away from normal position to effect movement of said carriage to release the stitching wire from 105 said feeding means, and means dependent upon the releasing of the stitching wire from said feeding means for effecting a step by step movement of said carriage longitudinally with respect to the adjacent edges 110 of the sheets.
10. Apparatus constructed in accordance with claim 9, wherein said last-named means includes a bumper operable by said treadle as the latter returns to normal position. 115
11. Apparatus constructed in accordance with claim 9, wherein said last-named means includes a bumper contacting with said carriage, resilient means normally urging said carriage toward said bumper, and connections between said bumper and said treadle for effecting movement of said bumper successively upon return of said treadle to normal position. 120
12. Apparatus of the character described 125

comprising means for holding a pair of wire sheets stationary with the edges thereof parallel to and slightly spaced from each other, a carriage arranged beneath said holding means, a trackway supporting said carriage for longitudinal movement with respect to the adjacent edges of the sheets, a guide carried by said carriage and having its upper end projecting between the adjacent edges of the sheets, feeding means adapted to receive the end of a stitching wire inserted between the wires of one sheet and to return it through the opposite end of said guide, a shaft adapted to drive said feeding means and longitudinally movable with said carriage, drive means for said shaft, and means for effecting movement of said carriage to release the stitching wire from said feeding means.

20 13. Apparatus constructed in accordance with claim 12, provided with means for effecting a step-by-step movement of said carriage upon the successive releasing of the stitching wire from said feeding means.

25 14. Apparatus constructed in accordance with claim 12, wherein the means for effecting movement of said carriage includes a treadle having a bias to normal position, and means controlled by the movement of said treadle back to normal position for effecting a step by step movement of said carriage upon the successive releasing of said stitching wire from said feeding means.

30 15. Apparatus of the character described comprising a pair of substantially U-shaped members adapted to receive the adjacent edges of a pair of wire sheets to hold them parallel to and slightly spaced from each other, a carriage arranged adjacent the edges of the sheets, a guide carried by said carriage and having its upper end projecting between the adjacent edges of the sheets, feeding means including a pulley and an endless belt for receiving the end of a stitching wire inserted between the wires of one sheet and adapted to return it through the opposite end of said guide, a trackway arranged beneath said carriage, wheels supporting said carriage on said trackway for longitudinal movement with respect to the adjacent edges of the sheets, a shaft connected to said feeding means and longitudinally movable with said carriage, means

for driving said shaft, a rod connected to said carriage, a toothed bar carried by said rod, and means engaging the teeth of said bar for effecting longitudinal movement of said carriage to release the stitching wire from said feeding means.

55 16. Apparatus constructed in accordance with claim 15, wherein said last-named means includes a bell-crank lever, a pawl carried by one end of said lever and engaging the teeth of said bar, a treadle shaft, a crank carried by said treadle shaft, a rod pivotally connected at one end to said crank and at its opposite end to the other end of said bell-crank lever, and a treadle having a bias to normal position and movable in one direction for rocking said treadle shaft.

60 17. Apparatus constructed in accordance with claim 15, wherein said last-named means includes a bell-crank lever, a pawl carried by one end of said lever and engaging the teeth of said bar, a treadle shaft, a 75 crank carried by said treadle shaft, a rod pivotally connected at one end to said crank and at its opposite end to the other end of said bell-crank lever, a treadle having a bias to normal position and movable in one direction for rocking said treadle shaft, and means controlled by the return of said treadle to normal position for effecting movement of said carriage.

70 18. Apparatus constructed in accordance with claim 15, wherein said last-named means includes a bell-crank lever, a pawl carried by one end of said lever and engaging the teeth of said bar, a treadle shaft, a 80 crank carried by said treadle shaft, a rod pivotally connected at one end to said crank and at its opposite end to the other end of said bell-crank lever, a treadle having a bias to normal position and movable in one direction for rocking said treadle shaft, a bumper contacting with said carriage, a spring normally urging said carriage toward said bumper, a worm-shaft adapted upon rotation to effect movement of said bumper, a worm-wheel associated with said worm-shaft, and connections between said wheel and said treadle for rotating said wheel upon return of said treadle to normal position.

85 In testimony whereof I affix my signature.
FRANK F. SCHMIEGE.
